DESIGN FOR AN ALPACA FUR AND LAMB-SKIN SLIPPER

Alexander Camerle, New York, N. Y.

Application April 18, 1944, Serial No. 113,295

Term of patent 3½ years

(Cl. D7—7)

To all whom it may concern:

Be it known that I, Alexander Camerle, a citizen of the United States of America, residing in city of New York, county of New York, and State of New York, have invented a new, original, and ornamental Design for an Alpaca Fur and Lambskin Slipper, of which the following is a specification, reference being had to the accompanying drawing, forming part thereof.

The figure on the drawing is a perspective view of an alpaca fur and lambskin slipper showing my new design.

I claim:

The ornamental design for an alpaca fur and lambskin slipper, substantially as shown.

ALEXANDER CAMERLE.
